UNITED STATES PATENT OFFICE.

JOHN MCNAUGHT CAMERON, OF EAST LAKE, ALABAMA.

CAST-METAL MONUMENT.

SPECIFICATION forming part of Letters Patent No. 498,506, dated May 30, 1893.

Application filed December 24, 1892. Serial No. 456,231. (No model.)

To all whom it may concern:

Be it known that I, JOHN MCNAUGHT CAMERON, a subject of Great Britain, residing at East Lake, in the county of Jefferson and State 5 of Alabama, have invented certain new and useful Improvements in Cast-Metal Monuments; and I do hereby declare the following to be a full, clear, and exact description of the invention, such as will enable others skilled in 10 the art to which it appertains to make and use the same.

My invention relates to improvements, in cast iron, or other cast metal monuments for graves; and the object of my improvements 15 are, first, to make a monument of the above described kind, of neat and pleasing design, that can be cheaply constructed, and will be easily handled, shipped and set up, a monument that can be finished to represent marble, 20 or stone of any description, and will last for a long time exposed to the weather; second, to so construct a cast metal monument, that the name, or inscription will be inserted in such a manner, as to be easily removed for 25 the purpose of changes, or additions, and that the inscription will be protected from the weather, by a plate of glass inserted in the inscription holder on the outside of the name. I attain these objects by certain novel features of construction, illustrated in the accompanying drawings, in which,—

Figure 1 is a vertical front view of a monument with base, showing the inscription in place. Fig. 2, is a vertical sectional view of 35 the same. Fig. 3, is a vertical back view of a monument without base, and shows the inscription holder, secured to the slab. Fig. 4, is a front view of the inscription holder, with the inscription and glass in place, before it 40 is attached to the slab.

Similar letters refer to similar parts throughout the several views.

The base A, is made of cast iron, or other metal, and can be formed in any of the usual 45 designs suitable for a monument. It is cast hollow as shown, and is left open on the bottom and is provided with a flange B, extending round the bottom edge, to hold it more securely in the ground, or for the purpose of 50 securing it to any desired material that may be placed under it, as a foundation. On the upper side of the base, it is provided with any

desired number of holes C. The said holes are for the purpose of securing the base to the slab, as hereinafter described.

55

The slab D, is made of cast iron, or other metal, of any suitable design, or form as shown, but may be made as a shaft or column if so desired; on the front outer edge is formed a bead E, or any other suitable ornamental 60 molding, extending round both sides and top, and also having a plain flange F, on the back of the outer edge, on the opposite side from the bead or molding; the bottom of the slab is provided with a like flange G, G' on both 65 sides, the said flanges being provided with two, or more screw bolts H cast in, or in any other manner secured in the metal, the said bolts being for the purpose of securing the slab to the base as shown, the bolts holding 70 the slab and base firmly together, by the aid of the nuts on the bottom of the bolts H, one of the said nuts I and bolt H, being shown in the sectional view; the said slab D, can be made without a base, the bottom extending 75 down to rest in the ground as shown in Fig. 3 if so desired. The main slab or casting is formed open in the center as shown, the said opening having on its front edge, a fillet, or ornamental molding O, to form a frame to the 80 opening. On the back of the said frame, is formed a rabbet I, extending round the opening, for the purpose of holding the inscription holder, the glass, and the inscription to place.

The inscription holder K, is made of cast 85 metal, with a recess formed on the face side, deep enough to hold the name plate L, and the glass M, to cover it. The said inscription holder is provided with a series of lugs N, N, to secure it to the back of the slab D, by a 90 series of screws as shown.

The patterns for the motto, or emblem P, are made separate from the pattern of the main slab D, and can be kept in a variety of designs, and emblems of various kinds. They 95 are secured to the pattern temporarily before molding, and can be changed as often as desired; the base A, the main slab D, and the inscription holder K, are all cast in separate pieces; the base and the slab D, are secured 100 together by the bolts and nuts as shown; the inscription holder, when the name plate and glass are inserted, is secured to the back of the slab D, by screws as shown.

Having thus described my invention, what I claim as new, and desire to secure by Letters Patent, is—

In a monument, a metallic slab D, having a recess J formed in the back of the slab, the said recess extending round the edge of an aperture formed in the center of the slab, a metallic back K to cover the aperture, having a projecting rim formed on its outer edge, a series of lugs N formed on the outside of the projecting rim of the back, the rim formed

on the outer edge of the back, inserted in the recess J formed in the slab D, and means to secure the back to the slab, substantially as described.

In testimony whereof I affix my signature in presence of two witnesses.

JOHN MCNAUGHT CAMERON.
